UNITED STATES PATENT OFFICE.

MARY E. WADE, OF WASHINGTON, DISTRICT OF COLUMBIA.

DESIGN FOR RIBBON.

SPECIFICATION forming part of Design No. 27,282, dated June 29, 1897.

Application filed April 6, 1897. Serial No. 631,030. Term of patent 7 years.

To all whom it may concern:

Be it known that I, MARY E. WADE, a citizen of the United States of America, and a resident of Washington, in the District of Columbia, have invented and produced a new and original Design for Ribbons, of which the following is a specification.

The nature of this design is illustrated by a drawing, forming part of this specification,

- o the figure of which represents a face view of a short piece of ribbon bearing the new design.

The design is primarily intended for the satin side of a woven silk ribbon about one and one-half inches wide, for use in a spiral form of artwork, and is intended to be worked into the ribbon in the loom.

The design consists of a series of stripes (shown in the drawing at 1, 2, and 3) running

parallel with each other along one selvage of the ribbon, separated from each other by stripes 4 and 5, the striped portion constituting something less than one-half the width of the ribbon, and the remainder forming a broad stripe 6, which, together with said stripes 4 and 5, is preferably white, the stripes 1, 2, and 3 being of a bright contrasting color, such as cardinal red.

Having thus described the said design, I claim as my invention and desire to patent under this specification—

The design for ribbons as herein shown and described.

MARY E. WADE.
